CLAIM

The ornamental design for a spacer for electrical outlet and switch mounting boxes, as shown and described.

DESCRIPTION

FIG. 1 is a perspective view of a spacer for electrical outlet and switch box showing our new design;

FIG. 2 is a front elevational view thereof on an enlarged scale;

FIG. 3 is a rear elevational view thereof on an enlarged scale;

FIG. 4 is a side elevational view thereof on an enlarged scale, the opposite side being a mirror image;

FIG. 5 is a bottom plan view thereof on an enlarged scale.

FIG. 1

FIG. 3

FIG. 2

FIG. 4

FIG. 5
